UNITED STATES PATENT OFFICE.

EMMA T. CRELLIN, OF BROOKLYN, NEW YORK.

DESIGN FOR A SUPPOSITORY.

SPECIFICATION forming part of Design No. 24,363, dated June 4, 1895.

Application filed April 19, 1895. Serial No. 546,431. Term of patent 7 years.

To all whom it may concern:

Be it known that I, EMMA T. CRELLIN, a citizen of the United States, residing in Brooklyn, Kings county, State of New York, have invented and produced a new and original Design for a Suppository, of which the following is a specification, reference being had to the accompanying drawings, showing the same.

Figure 1 is a plan view, and Fig. 2 is a plan view of the reverse side from Fig. 1. Fig. 3 is an axial sectional view.

1 is the front of the suppository, concave as at 2. 3 is the reverse side thereof, substantially hemispherical in shape, but having a slight depression 4 in its center. 15

What I claim is—

The design for a suppository, substantially as shown and described.

EMMA T. CRELLIN.
